United States Patent Office

Des. 184,152
Patented Dec. 23, 1958

184,152

AUTOMOBILE

Michael A. Skrovan, Sr., South Euclid, Ohio
Application July 25, 1956, Serial No. 42,380

Term of patent 14 years

(Cl. D14—3)

Fig. 3

Fig. 4

Fig. 1 is a view in side elevation of an automobile, showing my new design;

Fig. 2 is a top plan view;

Fig. 3 is a front view in elevation; and

Fig. 4 is a perspective view thereof.

The essential features of my design reside in those portions shown in full lines.

I claim:

The ornamental design for an automobile, substantially as shown and described.
